United States Patent Office.

HORACE EVERETT, OF PHILADELPHIA, PENNSYLVANIA.

Letters Patent No. 101,847, dated April 12, 1870.

IMPROVEMENT IN SHEET-METAL CANS.

The Schedule referred to in these Letters Patent and making part of the same.

I, HORACE EVERETT, of Philadelphia, county of Philadelphia, State of Pennsylvania, have invented an Improvement in Sheet-Metal Cans or Cases, of which the following is a specification.

Nature and Object of the Invention.

My invention relates to sheet-metal cans or cases, the joints of which are made without the aid of solder; and

My invention consists in forming in the body of the can, adjacent to the lapped joint, a crease which will prevent the slipping of the joint during the application of the bottom or head to the case.

Description of the Accompanying Drawing.

Figure 1 is a perspective view of a portion of the body of a sheet-metal can or case, showing the preparatory step taken in forming the joint.

Figure 2, a view of the joint complete.

General Description.

In fig. 1, A represents a strip of sheet metal, bent to a cylindrical shape so as to form the body of the can or case, the opposite ends, *a* and *a'*, of the strip being folded, and the fold of one fitting within the fold of the other, so as to form the usual lapped joint.

If solder be used to render this joint permanent, the bottom or head of the case could be applied by the aid of machinery without any difficulty, and there would

be no need of my invention, but numbers of cans or cases, such, for instance, as those for containing caustic alkali, are made by preference without soldering the joint.

In applying the heads or bottoms by machinery to bodies having plain unsoldered lapped joints, as shown in fig. 1, many of the cans are spoiled, owing to the tendency of the ends of the strip A, of which the body is composed, to slip in the direction pointed out by the arrows.

In order to prevent this, I form in the body of the can, adjacent to the lap joint, a crease, *b*, which forms an internal rib for preventing the displacement of the joint during the application of the bottom or head of the can to the body.

It is not necessary that the crease shall extend from end to end of the body, as two or more indentations only may be made adjacent to the joint.

Claim.

The crease or indentation *d*, made in the body of the can, in the position described.

In testimony whereof I have signed my name to this specification in the presence of two subscribing witnesses.

HORACE EVERETT.
